UNITED STATES PATENT OFFICE.

WILLIAM STUEBING, JR., OF CINCINNATI, OHIO, ASSIGNOR TO THE STUEBING-COWAN COMPANY, OF CINCINNATI, OHIO, A CORPORATION OF OHIO.

LIFTING TRUCK.

Application filed January 21, 1926. Serial No. 82,676.

The present invention relates to lifting trucks of the type in which the steering and draft handle or tongue is operative to lift the load.

5 Among the objects to which the invention is addressed is to provide an improved lifting truck whereof the steering tongue may be operated to lift the load when said tongue is swung in a plane other than that of the 60 longitudinal center line of the truck. Lifting trucks of this class are commonly designated as "side-lift" or "angle-lift" trucks, and possess the advantage of being operable to lift the load in relatively limited spaces 10 15 20 25 30 35 40 45 50 55 60 65 70 75 80 85 90 95 100

wherein it is difficult or impossible to operate the lifting mechanism by swinging the tongue in the plane of the longitudinal center line of the truck. In all practical lifting-trucks the load-bearing and lifting frame or platform is arranged to move upwardly in a direction parallel to the vertical plane of the longitudinal center-line of the truck, although in many instances the lifting platform is also arranged to move forward or backward as it rises vertically. In lifting trucks of the straight-forward lift type, therefore, the operating tongue (usually the steering-tongue) has ordinarily been arranged to swing in the same place of motion as that of the lifting platform. This permitted the necessary connections between the lifting platform and the tongue to be simple and direct and to be moved in one general direction during the lifting operation, as may be observed for example in United States Letters Patent No. 1,104,533 to C. E. M. Miller, patented July 21, 1914, No. 1,257,650 to W. Stuebing, Jr., patented February 26, 1918, and No. 1,373,069 to 40 45 50 55 60 65 70 75 80 85 90 95 100

Hennessy, patented Mar. 29, 1921. In side-lift trucks, however, since the lifting-tongue must be operable as such in numerous planes other than the vertical plane of the longitudinal center-line of the truck, there must be, somewhere in the train of connections between the tongue and the elevating platform as a whole, a connecting joint or point whereat the pivotal motion of the tongue in its vertical plane may be transmuted into motion in or parallel to the plane of the truck's longitudinal center line to raise the elevating platform regardless of whether the tongue is swung on the center line or to either side thereof. In all, or substantially all, types of practical side-lift

trucks in commercial use prior to the present invention the provision of such joint has involved either mechanical complication and multiplicity of parts, or else defects or operative limitations of one sort or another, all of which undesirable defects or limitations in the present invention is calculated to obviate.

In the present invention simplicity of structure has been attained through the provision of direct connection between the steering tongue and the elevating frame, the specific embodiment illustrated having the steering tongue provided with a unitary rigid lifting member extending between the steering tongue and elevating frame and capable of maintaining its operative relationship to lift the frame regardless of movements of the steering tongue to various steering positions, the arrangement of the parts being such that as the steering tongue is swung laterally to different steering positions, the lifting member, positively and permanently connected, with the steering tongue, swings with it and assumes different angular positions relative to the elevating frame corresponding to the angular steering positions of the tongue. Such an arrangement not only simplifies side-lift truck construction, but promotes other advantages, as, for example, the possibility of having the connecting joint or point previously mentioned occupy any mechanically convenient position relative to the other parts of the structure, the position of this point not necessarily being close to the vertical axis of the truck's steering post (as is the case in many structures shown in existing patents). These features in combination with others hereinafter described and claimed differentiate the present invention from the trucks hitherto in use, and may be better understood from a consideration of a particular illustrative embodiment thereof hereinafter described with reference to the accompanying drawings, in which:

Fig. 1 is a plan view of a lifting truck embodying the invention, showing the elevating frame in its lowered position and the lifting mechanism in position to elevate the load;

Fig. 2 is a central sectional view of the same, but showing the lifting mechanism disconnected from the load;

Fig. 3 is a view in side elevation, showing the elevating frame in its uppermost position.

tion, locked in uppermost position and with the lifting mechanism disconnected therefrom.

The truck shown for the purposes of illustrating the invention has a main frame 5 and a load supporting elevating frame 6. A steering head 7 is rotatably mounted in a transverse yoke 8 forming a part of the main frame and to which yoke the side bars 9 of the main frame are rigidly connected as by means of bolts 10 as best shown in Figs. 1 and 2. The elevating frame is supported on the main frame by means of similar links 11 and 12 pivotally connected to the main frame 10 at the front and rear ends thereof.

For the purpose of permitting the lifting and lifted elements to assume various different angular positions relative to each other, an arcuate angular member 14 is secured to the elevating frame in position to be engaged by a cooperating tension member or hook 15 pivoted at 16 to the steering handle, said members being so formed that they may readily be interengaged and disengaged, one member occupying a certain normal position relative to the other when the steering tongue is in its central straight-forward position, and one of said members being extended laterally from said normal position a substantial distance, i. e. a distance sufficient to permit interengagement of said members when said steering handle is in different steering positions to permit side or angle lift.

Normally the hook 15 is held in elevated position by means of a spring 17 and is connected with the arcuate member 14 by pressure of the foot upon a pedal projection 18 shown in Fig. 1.

The member 14 may well be so formed that the center of the arcuate path along which the members 14 and 15 may connect, lies to the rear of the vertical axis of the steering head 7 when the elevating frame is in lowered position. The hook 15 may be formed with its engaging face either straight laterally of the truck, or concave, but if concave, it should be formed on a slightly greater arc than that of the arcuate member 14 to accommodate the relative rocking movement during the lifting operation which rocking movement occurs as the arcuate member moves forward toward the center of the steering swivel.

By providing one of the interengaging members 14, 15 with extended surface affording a succession of operative engagement positions as the steering head is turned to one side, the member 15 which is connected to the handle, may be arranged to swing in the plane of the handle, thus avoiding any requirement for a joint permitting lateral movement of this member relative to the handle.

Any suitable lock may be provided for holding the elevating frame in its uppermost position. As shown, a locking hook 20 is pivotally mounted on the hook 8, and posi-

tioned to engage a corresponding hook 22 of the elevating frame. This hook is normally urged into locking position by means of a spring 23, but may be released by pressure on the forwardly extending pedal projection 21 70 forming a part of the locking member.

It will be understood that the invention may be variously modified and embodied within the scope of the subjoined claims.

What I claim is:

1. A lifting truck comprising, in combination, a main frame having a swivelled steering head, an elevating frame mounted on the main frame and movable upwardly relative thereto, a vertically swinging steering lever, a direct connection between the steering lever and elevating frame comprising interengageable members carried respectively by the steering lever and elevating frame, one of which extends laterally a substantial distance from its position of engagement with the other when the steering lever is in central position and permitting interengagement in different steering positions of the handle. 75

2. A lifting truck comprising, in combination, a main frame having a swivelled steering head, an elevating frame mounted on the main frame and movable upwardly relative thereto, a vertically swinging steering lever, a direct connection between the steering lever and elevating frame comprising interengaging hook members, one of which has an arcuate engaging portion substantially as and 80 85 90 95 100

3. A lifting truck comprising, in combination, a main frame having a swivelled steering head, an elevating frame mounted on the main frame and movable upwardly relative thereto, a vertically swinging steering lever, an arcuate hook member secured to the elevating frame, and a hook member pivoted to the steering lever to swing vertically in the plane of movement of the steering lever and engageable with and disengageable from the arcuate hook member in various steering positions. 105 110 115

4. A lifting truck comprising, in combination, a main frame having a swivelled steering head, an elevating frame mounted on the main frame and movable upwardly relative thereto, a vertically swinging steering lever, a member carried by the elevating frame and extending laterally a substantial distance, a member carried by the steering handle and engageable with and disengageable from different portions of said laterally extending member in various steering positions to lift the elevating frame. 120 125

5. A lifting truck comprising, in combination, a main frame having a swivelled steering head, an elevating frame mounted on the main frame and movable upwardly relative thereto, a vertically swinging steering lever, a member presenting a hook extending 130

transversely of the elevating frame on an arc the center of which lies rearwardly of the axis of the swivelled head, and means for connecting the handle to the arcuate hook substantially as and for the purpose described.

6. A lifting truck comprising in combination a main frame having a swivelled steering head, an elevating frame mounted on the main frame and movable upwardly relative thereto, a vertically swinging steering lever, an arcuate hook member secured to the elevating frame in such position that the center of the arc thereof lies rearwardly of the axis of the swivelled steering head, and a hook member pivoted to the steering lever to swing vertically and engageable with the arcuate hook member in various steering positions to lift the elevating frame.

7. A lifting truck comprising in combination a main frame, an elevating frame, a steering lever, a hook extending transversely of the elevating frame on an arc whose center lies forward of the hook, and means connecting the steering lever to the hook to lift the elevating frame.

8. A lifting truck comprising, in combination, a main frame having a swivelled steering head, an elevating frame having a surface extending laterally a substantial distance, a vertically swinging steering lever, a hook pivotally carried by the steering lever and engageable with the elevating frame at different points of said surface to lift said elevating frame.

35 9. A lifting truck, as defined in claim 2, comprising a spring tending to disengage the hook members.

10. A lifting truck, as defined in claim 2, comprising a spring tending to disengage one hook member from the arcuate engaging portion.

11. A lifting truck comprising, in combination, a main frame, an elevating frame mounted thereon and arranged to be upwardly movable relatively thereto, a steering swivel mounted upon said main frame, a steering tongue pivotally mounted upon said steering swivel and provided with a rearwardly extending lifting member arranged to be moved by said steering tongue to raise said elevating frame, means rigidly mounted upon said elevating frame provided with surface extending a substantial distance to the right and left of the longitudinal center-line of said elevating frame and so positioned as to be in the operative path of the free end of said lifting member when the latter is operated to raise said elevating frame whether said lifting member be operated to the right or left of said center line, whereby said lifting member may engage said surface at various points to raise said elevating frame when said steering tongue is operated to the right or left of its straight forward position.

12. A lifting truck comprising, in combination, a main frame, an elevating frame mounted thereon and arranged to be longitudinally and upwardly movable relative thereto, a steering swivel mounted upon said main frame, a steering tongue pivotally mounted upon said steering swivel, a lifting member operatively connected to said steering tongue to raise said elevating frame, said elevating frame being provided with surface extending a substantial distance to the right and left from its longitudinal center line and so positioned as to interpose different portions of said surface in the operative paths of said lifting member in accordance with the positions wherein said tongue is operated to the right or left of the longitudinal center line of the truck.

13. A lifting truck comprising in combination a main frame having supporting and steering wheels, a steering tongue provided with a pivotal connection to said steering wheels permitting said tongue to be swung in a vertical plane and having a rearwardly extending lifting member, an elevating frame upwardly movable relatively to said main frame and having a lifting contact surface positioned to form a pivotal connection with the free end of said lifting member, one of said pivotal connections being free to move in an arcuate path on either side of the longitudinal center line of the truck as said steering tongue is turned laterally to various steering positions, and means, independent of said lifting member, to lock said elevating frame in raised position.

14. A lifting truck comprising in combination a main frame having supporting wheels and a steering wheel mounted to turn on a vertical axis, a steering tongue having a point of connection with said steering wheel and provided with a rearwardly-extending lifting member, an elevating frame upwardly movable relatively to said main frame and having a contact surface positioned to afford a point of connection with the free end of said lifting member, one of said points of connection being movable a substantial distance in a horizontal arcuate path in accordance with lateral movements of said steering tongue as the latter is turned to various steering positions whereby the parts may maintain operative lifting relationship when said tongue is in said various positions, and means independent of said lifting member to lock said elevating frame in its elevated position.

15. A lifting truck comprising in combination a main frame having supporting wheels and a steering wheel mounted to turn on a vertical axis, a steering tongue pivotally connected to said steering wheel and provided with a rearwardly-extending lifting member, an elevating frame upwardly movable relatively to said main frame and having a surface to making lifting contact with the free,

- end of said lifting member, said lifting member being arranged to be turned horizontally by and with said steering tongue a substantial distance without moving out of operative 5 lifting position relative to said surface whereby said elevating frame may be lifted through said tongue when the latter occupies various steering positions substantially to one side of its straight forward position.
- 10 16. A lifting truck comprising in combination spaced supporting wheels, an elevating frame upwardly movable relatively thereto, a draught tongue mounted to pivot vertically and horizontally relatively to said frame and provided with a rigid lifting member movable by and with said tongue to raise said frame relatively to said wheels, and an element integral with said frame for cooperative lifting contact with the free end of said rigid lifting 15 member, the parts being shaped and positioned to permit said tongue to be operated at substantial distances to one side of its straight forward position to lift said frame without disengagement of said lifting member from said element.
- 20 17. A lifting truck comprising, in combina-
25

tion, a main frame having supporting and steering wheels, an elevating frame mounted thereon for upward movement relatively thereto, elevating and steering means including a tongue connected to said steering wheels to guide the same, pivoted to be swung vertically relatively thereto and provided with a lifting member having a rearwardly-extending free end, means integral with said elevating frame shaped and positioned to be engageable by said free end of said lifting member when said tongue is swung vertically in a forward direction to raise said elevating platform, said free end and said last-named means being relatively shaped and positioned to permit said lifting member to describe circular movement relative to said last-named means without breaking contact therewith as said tongue is swung laterally to various steering positions, and means independent of said member for holding said elevating frame in elevated position.

In testimony whereof, I have signed my name to this specification this seventeenth day of December, 1925.

WILLIAM STUEBING, Jr.
